UNITED STATES PATENT OFFICE.

WILLIAM W. METZGER, JULIAN A. ALTENDORF, AND CALVIN M. VERRILL, OF LOS ANGELES, CALIFORNIA.

NON-GLARE HEADLIGHT.

1,155,600.

Specification of Letters Patent.

Patented Oct. 5, 1915.

Application filed April 13, 1915. Serial No. 21,043.

To all whom it may concern:

Be it known that we, WILLIAM W. METZGER, JULIAN A. ALTENDORF, and CALVIN M. VERRILL, citizens of the United States, residing at Los Angeles, in the county of Los Angeles, State of California, have invented new and useful Improvements in Non-Glare Headlights, of which the following is a specification.

10 This invention relates particularly to automobile head lights and the like; and it is a primary object to provide a simple and effective means for completely obviating the glare of the ordinary headlight or of any 15 other light where it is desirable to eradicate the glare.

It is well known that automobile head lights as now used throw such a strong and concentrated light as to practically blind 20 any person toward whom they are advancing.

Our invention so completely obviates the glare of the head light that one may look directly into our light without discomfort; 25 and, at the same time, our head light throws a most effective light ahead and very efficiently illuminates the road.

One of our primary objects is, while eliminating the glare, to not decrease the 30 lighting efficiency of the head light; and this object, and others we accomplish by means of a device shown in the accompanying drawings and described in the following specification.

35 For the purpose of this specification we illustrate in the accompanying drawings a preferred and specific form of our device in which drawings—

Figure 1 is a vertical longitudinal section 40 of a head light constructed after our invention, Fig. 2 is a perspective showing the non-glare member thereof, and Fig. 3 is a front elevation of our device.

In the drawings we have illustrated a 45 head light casing 10 which may typify any head light casing of any size or configuration. This casing has the usual front glass 11 and reflector 12. It will be understood that our device may be applied to any form 50 or size of head light, and will operate in conjunction with a reflector of any configuration.

The glare of the automobile head lights is due to excessively strong concentrated light 55 thrown from the reflector, the light being

radiated directly and without interruption of any kind from the lamp 13 to the reflector 12.

Our method of overcoming the glare comprises fundamentally the interposition 60 of a member between the lamp 13 and the reflector 12, it being the function of this member to partially and diffusely transmit the light through from the lamp to the reflector. Although there are many forms 65 which may be used for this member, we prefer to use a form illustrated in the drawings, comprising a bell shaped member 14 of a suitable translucent material. Preferably the material is glass frosted on both sides; 70 and one side, preferably the exterior, is superficially treated with the substance known as gold size. This substance has the effect of putting a certain amount of gloss on the exterior surface of the frosted glass; 75 and, although our arrangement operates very satisfactorily without the size, the application of size brings the effect to the highest state of perfection.

The member 14 may be mounted around 80 the lamp in any suitable manner, preferably being mounted as shown in Fig. 1. Two rubber washers 15 are used and a small spring 16 presses the rear washer against the flange 14^a of the member 14 and presses the 85 flange forwardly against the front washer 15. The bell shaped member 14 is thus held securely in position without danger of breaking.

The front end of the bell shaped member 90 is entirely open as shown at 14^b. Light from the lamp is radiated directly forwardly. The translucent member 14 is illuminated by the lamp, and the rays of the light pass from the translucent member to 95 the reflector. The resulting beam of light thrown from the reflector is very powerful and the illumination is in no way inferior to the illumination by the ordinary head light; but the glare is entirely eliminated. 100

Having described a preferred form of our invention, we claim:

A non-glare headlight, embodying in combination a lamp, a reflector behind and around the lamp, said reflector adapted normally to throw the light from said lamp in a concentrated stream ahead, and a translucent member around and behind the lamp and of such extent as to intercept the light from the lamp which would otherwise be 110

transmitted directly to the reflector, the front of said member being open to allow direct radiation from the lamp ahead independently of the reflector, whereby the reflector is illuminated only by diffused light from the translucent member and that portion of the light which is transmitted forwardly from the lamp is allowed to be freely transmitted independently of the reflector.

In witness that we claim the foregoing we have hereunto subscribed our names this 7th day of April 1915.

W. W. METZGER.
J. ALTENDORF.
C. M. VERRILL.
